UNITED STATES PATENT OFFICE.

HORACE FISHER, OF LETCHWORTH, ENGLAND, ASSIGNEE TO WILLIAM EDWARD GARFORTH, OF PONTEFRACT, YORKSHIRE, ENGLAND.

APPARATUS FOR INTERMITTENTLY FEEDING CINEMATOGRAPH AND SIMILAR FILMS.

1,128,861.

Specification of Letters Patent.

Patented Feb. 16, 1915.

Application filed June 6, 1914. Serial No. 843,377.

To all whom it may concern:

Be it known that I, HORACE FISHER, photographic works manager, a subject of the King of Great Britain, residing at 12 Balfour dock road, Letchworth, Hertfordshire, England, have invented certain new and useful Improvements in Apparatus for Intermittently Feeding Cinematograph and Similar Films, and of which the following is a specification.

This invention relates to an improved construction of apparatus by which cinematograph and similar films are intermittently fed in line with the lens of a cinematograph apparatus, either for projecting an image or for receiving an impression on the film.

The apparatus according to this invention comprises a shaft adapted to be rotated at a uniform speed, which shaft carries an eccentric 20 engaging a vertically movable slide in such a manner that upon rotation of the said shaft, the slide has imparted to it reciprocating motion (similar to that of the piston of an engine) having a brief period of rest 25 at either end of the stroke accelerating its movement to the center of the stroke and then retarding until it arrives at the end of its movement. The said slide is provided with a stationary jaw and with a 30 movable jaw between which jaws the film is intermittently gripped, both jaws projecting in a direction at right angles to the slide, said movable jaw being fixed to a spindle carried in a bearing in said slide 35 and adapted to be closed by a spring or its equivalent against the fixed jaw and to be opened by mechanical connections between the said eccentric-carrying shaft and a member capable of angular movement on 40 said spindle, which member is adapted when desired to release the grip on the film, to coact with the movable jaw or the spindle carrying the said jaw to move the latter against the action of said spring to open the 45 jaws.

The invention will be described with reference to the accompanying drawings.

Figure 1 is a side elevation of the slide, the jaws and the operating mechanism, but 50 shown detached from the carrying and supporting framework, and illustrated with the jaws in the closed position. Fig. 2 is a rear elevation of this mechanism, and Fig. 3 is a side elevation similar to Fig. 1, but showing

the opposite side of the mechanism there 55 illustrated. Fig. 4 is a view similar to Fig. 1, but showing the slide about midway of its downward travel, with the jaws in the closed position, and Fig. 5 is a view corresponding to Fig. 4, but showing the opposite side of 60 the mechanism. Fig. 6 is a side elevation of the mechanism, showing the slide in its lowest position, and with the jaws still closed, and Fig. 7 is a similar view of the opposite side of the mechanism. Fig. 8 65 shows the slide at an early period in its return upward motion, with the jaws open, Fig. 9 being a view corresponding to Fig. 8, but showing the opposite side of the mechanism. By way of example the subject 70 matter of the present invention is shown applied to a cinematographic camera which is sufficiently illustrated at Figs. 10 to 12 inclusive, Fig. 10 being a right hand side elevation of the camera with the side plate of 75 the case removed. Fig. 11 is a left hand side elevation of the camera, also with the side plate removed, and Fig. 12 is a vertical section on the line X—Y of Fig. 11 looking to the right.

Referring more particularly to Figs. 1 to 9 of the accompanying drawings, the reciprocating slide 1 is supported and bears against a vertical plate portion 2, Fig. 2, forming part of the fixed frame of the 85 camera, and which lies in a plane parallel with the axis of the lens and at a distance on one side of same; the slide 1 moves vertically between two guide ribs 3, Fig. 6, fixed to the part 2 of the frame.

A shaft 4, carried in bearings on the framework, passes through a vertical slot 5 in the slide 1, and carries an eccentric 6 which rests between two ribs 7 projecting from the face of the slide 1. Above the 95 said ribs 7 the slide 1 is formed with an outstanding gripping jaw 8, and an opposed oscillating gripping jaw 9 is mounted on an arm 10 carried on a spindle 11 which passes through a rearwardly extending sleeve 12 100 on the slide 1. The opposite end of the said spindle 11 carries a freely mounted crescent 13, Figs. 2 and 3, which is caused to rock to right or left by means of a second eccentric 14 mounted on the shaft 4 105 carrying the first eccentric 6. The rotations of the shaft 4 cause the first eccentric 6 to reciprocate the slide vertically, and the

second 14 to rock the crescent 13. The spindle 11 carrying the oscillating jaw 9 also has an arm 15, Fig. 3, keyed to the said spindle 11, and an outstanding pin 16 on the arm 15 intercepts a projection 17 on an upper extension of the crescent 13, which projection 17 is connected by a spring 18 to the said arm 15. The effect of this construction is, that when the crescent 13 is 10 rocked in one direction, the connecting spring 18 becomes tensioned and the jaws 8 and 9 are resiliently held together, while when the crescent 13 is rocked in the other direction, the jaws are opened by reason of 15 the projection 17 on the crescent 13 contacting with the pin 16 projecting from the arm 15 carried by the spindle 11.

The jaws 8 and 9 are suitably faced with velvet, one jaw having an entire velvet face, 20 and the other having a recess (not necessary to illustrate in the drawings) cut longitudinally in the same at right angles to the direction of movement of the film and containing in that recess a narrow strip 25 of velvet. The pile of the velvet of the strip pressing the film toward the completely covered face of the opposite jaw, slightly bends the film as it is gripped and insures a good hold being taken on the film 30 without injury to it.

The apparatus hereinbefore described for intermittently feeding cinematograph and similar films, is shown applied to a cinematographic camera at Figs. 10 to 12 inclusive of the accompanying drawings. Referring particularly to Figs. 10 and 12, the shaft 4 carrying the eccentrics 6 and 14 and which is carried in bearings of the framework 2 and by a bearing bracket 19, shown 40 by dotted lines at Fig. 2, is revolved through a pinion 20 driven by a spur wheel A on a driving shaft B revolved by a handle C, and the shaft 4 is preferably fitted with a fly wheel 21. The driving shaft B is fitted 45 with a pulley D, which communicates motion by a driving band E to a pulley F on a spindle F¹, Fig. 11. The spindle F¹ extends through the vertical frame 2, see Fig. 11, and receives a film holder consisting of 50 a box F² containing a reel which is driven by the spindle F¹ while the box is held stationary and the reel operates to draw the film H from a reel in a similar film holder F³. The film H passes from the film holder 55 F³ over the rear face of a stationary guide plate J formed with an aperture J¹, Fig. 12, opposite the lens K, Fig. 11, below which plate J the jaws 8, 9 of the feed mechanism hereinbefore described are located to draw 60 the film intermittently from the film holder F³. The film then passes through a tension device indicated at L, Fig. 10, and from thence to the film holder F². The revolving shutter P, Figs. 11 and 12, is operated 65 through the medium of a pinion P¹ engag-

ing the driven spur wheel A, the shaft of the pinion P¹ carrying a bevel wheel engaging a bevel wheel P² on the shaft of the shutter P, see Fig. 11.

With this construction of camera, when 70 the operating handle C is revolved, the spur wheel A, by the pinion 20 revolves the shaft 4, and so operates the jaws 8, 9 in the manner already described, intermittently drawing the film from the film holder F³ past 75 the stationary guide plate J; the slack of the film H is taken up and the film wound on the reel in the film holder F², the spindle of which F¹ is operated as before described by the driving band E and the pulley F. 80

What I claim as my invention and desire to secure by Letters Patent is:—

1. Mechanism for feeding films past the lens in a wall of the case of cinematographic apparatus; comprising in combination a 85 vertical fixed frame within said case, a slide, vertical guides on said frame, a shaft rotatably carried at one end in a bearing in said frame and at the other end in a standard in said case, means for rotating said 90 shaft, an eccentric connection between said shaft and said slide to impart reciprocatory movement to the latter, a film gripping jaw fixed to said slide and projecting therefrom at right angles to the plane containing the 95 slide, a spindle supported in bearings in said slide, a movable jaw fixed to said spindle and adapted to co-operate with said fixed jaw to grip the film, a mechanical connection between said shaft and said spindle 100 operative to rock said spindle upon the completion of the downward movement of said slide to open the jaws and release the film, and resilient means operative at the completion of the upward movement of said 105 slide to cause the movable jaw to approach the fixed jaw to grip the film during the downward movement of said slide.

2. Mechanism for feeding films past the lens in the wall of the case of cinematographic apparatus; comprising in combination a vertical fixed frame within said case, a slide, vertical guides on said frame for 110 said slide, a shaft rotatably carried at one end in a bearing in said frame and at the other end in a standard in said case, means for rotating said shaft, an eccentric connection between said shaft and said slide to 115 impart reciprocatory movement to the latter, a film gripping jaw fixed to said slide and projecting therefrom at right angles to the plane containing the slide, a spindle supported in bearings in said slide, a movable jaw fixed to said spindle and adapted to co-operate with said fixed jaw to grip the film, an arm fixed to and projecting radially from said spindle, a second arm rotatably carried by said spindle and projecting radially therefrom in the opposite direction 120 to the aforesaid arm, a tension spring con- 125

necting the outer ends of said radial arms, a mechanical connection between said second arm and said shaft to rock said arm on said spindle during the reciprocation of said slide, an abutment on said fixed arm adapted to be acted upon by said second arm to move said spindle and the jaw carried thereby away from the fixed gripping jaw when said second arm is rocked toward said fixed arm during the upward movement of said slide the said spring becoming stressed during the downward movement of said slide owing to the loose arm being moved in the opposite direction by said mechanical connection whereby a film is resiliently gripped between the said gripping jaws.

3. Mechanism for feeding films past the lens in a wall of the case of cinematographic apparatus; comprising in combination a vertical fixed frame within said case, a slide, vertical guides on said frame for said slide, a shaft rotatably carried at one end in a bearing in said frame and at the other end in a standard in said case, means for rotat- 20 ing said shaft, an eccentric connection be- 25 tween said shaft and said slide to impart re- 30 ciprocatory movement to the latter, a film gripping jaw fixed to said slide and pro- 35 jecting therefrom at right angles to the plane containing the slide, a spindle sup- 40 ported in bearings in said slide, a movable jaw fixed to said spindle and adapted to co- 45 operate with said fixed jaw to grip the film, an arm fixed to and projecting radially from 50 said spindle a two-armed lever rotatably carried by said spindle the upper arm of 55 which radiates in the opposite direction to that of the aforesaid fixed arm, an eccentric fixed to said shaft to engage the cres- 60 cent-shaped lower end of said two-armed lever so that upon the rotation of the said eccentric and the simultaneous raising and 65 lowering of the said slide the upper arm of said two-armed lever is respectively rocked 70 toward and away from said fixed arm, a tension spring connecting the upper ends of 75 said two-armed lever and said fixed radial arm, an abutment on said fixed arm adapted to be acted upon by said two-armed lever 80 to rock said spindle and move the movable gripping jaw away from said fixed gripping jaw to release the film during the upward movement of said slide while upon 85 the downward movement of said slide the two-armed lever is, by the eccentric, rocked so as to stress said spring and turn said spindle so that said film is resiliently gripped during the downward movement of 90 said slide.

turn said spindle so that said film is resili- 95 ently gripped during the downward movement of said slide.

4. Mechanism for feeding films past the lens in a wall of the case of cinematographic apparatus; comprising in combination a slide, a vertical fixed frame within said case, vertical guides on said frame for said slide, a horizontal shaft carried near one end in a bearing in said frame, said shaft passing through a vertical slot in said slide, an eccentric disk fixed to the end of said shaft projecting through said slot, upper and lower projections on said slide against which 65 projections the eccentric disk bears, a standard in said case to rotatably support the other end of said shaft, means to impart rotation to said shaft, and said eccentric disk to reciprocate said slide, a film gripping jaw fixed to said slide and projecting therefrom at right angles to the plane containing the latter, a spindle parallel with said shaft and supported in bearings in said slide, a movable jaw fixed to said spindle and adapted to be rocked to coöperate with said fixed jaw to grip the film, an arm fixed to and projecting radially from said spindle, a two-armed lever rotatably carried by 70 said spindle the upper arm of which radiates in the opposite direction to that of the aforesaid fixed arm, an eccentric fixed to said shaft between said frame and said standard to engage the crescent shaped end of the lower arm of said two-armed lever to 75 rock said lever upon rotation of said eccentric, a tension spring connecting the upper ends of said two-armed lever and said fixed radial arm, an abutment on said fixed arm adapted to be acted upon by said two-armed lever to rock said spindle and move the movable gripping jaw away from the fixed gripping jaw to release the film during the upward movement of said slide while upon 80 the downward movement of said slide the two-armed lever is, by the eccentric, rocked so as to stress said spring and turn said spindle so that said film is resiliently gripped during the downward movement of 85 said slide.

In witness whereof I have hereunto set my hand in the presence of two witnesses.

HORACE FISHER.
